ROBERT H. BEAUMONT, OF RADNOR, PENNSYLVANIA, ASSIGNOR TO R. H. BEAUMONT CO., OF PHILADELPHIA, PENNSYLVANIA, A CORPORATION OF PENNSYLVANIA.

CABLE-WINDING MECHANISM.

Application filed May 6, 1926. Serial No. 107,098.

This invention relates to mechanism for winding cables or ropes, and to a type more particularly useful in connection with systems for storing and handling materials such as coal, gravel or sand. In a typical system of the sort to which I have made reference, an extensive out-door storage field is provided over which the material is initially distributed, and wherefrom it is subsequently reclaimed as needed by a drag scraper capable of adjustable radial traverse over the field area relative to a fixed focal point under power applied to the tow cable. In winding mechanism heretofore used for the latter purpose, the drums for the opposite ends of the cable were both driven at a uniform high speed rate, and obviously, the power required was dependent upon the effort necessary to pull the full loaded scraper at the predetermined high speed rate. Now, if the loaded travel of the scraper were effected at a comparatively slower speed rate than the above, and the empty scraper returned at a relatively higher speed, the average operative speed could be maintained with less applied power, and therefore with less costly equipment than heretofore required.

The object of my invention is to take advantage of the principle just recounted, and with this end in view, to provide winding mechanism with the shafts of the winding drums for opposite ends of the cable adapted to be driven at different speeds, and in which the driving and speed relation between said drums may be changed as desired or required for the purposes above outlined.

In the drawings Fig. I is a plan view, more or less diagrammatically represented, of a material storage and handling system with which the winding mechanism of my invention may be used to advantage.

Fig. II is an elevation of the organization as viewed from the bottom of Fig. I; and Fig. III is an illustration on a larger scale—than the preceding—showing a plan view of the winding mechanism whereby I attain the object above outlined.

In order to facilitate more ready understanding of my invention, I will first proceed to describe in a general way, the material storage and handling system of Figs. I and II in connection with which it is particularly useful. As shown, such a system comprises an extensive out-door storage area 10, which, in the present instance, is substantially rec-

tangular in outline, the upper, lower and rear sides of the field being skirted by a number of posts 11 for a purpose to be presently explained. The reclamation point is located mid-way of the front side of the field 10; and a tower 12 at this point provides guides for a skip bucket 13 whereby the material may be elevated from a hopper 14 located below the ground level, to a chute 15 for gravity discharge either to form an initial mound or pile P for discharge into cars 16 running on rails that extend through the tower above the hopper 14 aforesaid. In the process of storing out, the material is taken from the initial pile P, and distributed over the storage area 10 by a drag scraper 17 which is actuated through the medium of a tow cable 18, by winding mechanism housed within an inclosure 19, in the present instance located near the upper left hand corner of the field. The movements of the cable 18 are guided by a system of sheaves whereof those designated 20, 21—Fig. II—are positionally fixed and located at a focal point on the tower 12 while the others marked 22, 23 are supported by guy wires 24 capable of being attached between different pairs of the posts 11 about the field edge. By this arrangement, radial travel of the scraper 17 relative to the focal point at which the sheaves 20, 21 are located, may be varied so that any desired area of the storage field may be operated upon. In reclamation, the process is of course reversed, that is to say, the drag scraper 17 is turned about on the cable and operated to bring its charges to the focal point over a ramp 25, Fig. II, by which the material is directed into the hopper 14 previously mentioned.

Coming now to my improved winding mechanism or two speed drag winder, it will be observed from Fig. III that the same comprises two drums designated 26, 27, these being mounted free on separate shafts 28, 29, that are journaled in upstanding bearings 30 of an appropriate base 31. With the drums 26, 27 are associated high and low speed gears 32, 33 and 34, 35 respectively, which are fixedly secured to the shafts 28, 29. The raised faces 36 of the low speed gears 34, 35 are conically recessed for cooperation with correspondingly tapered flanges 37 on the contiguous ends of the drums 26, 27; and suitable means, such for example as screws 38, are provided to

enable adjustment and maintenance of the friction couplings thus formed between said drums and the shafts 28, 29 whereon they are mounted. Journalled in bearings 39 intermediate the drums 26, 27, is a drive shaft 40 that is equipped, at one end, with a pulley 41 for coordination, by belt, with a source of power,—an electric motor for example. Splined on the shaft 41 for simultaneous axial shifting thereon, are a pair of pinions 42, 43 that are common to, and capable of being brought alternately into mesh with the speed gears 32, 33 and 34, 35 respectively,—suitable means, herein shown in the form of a hand lever 44, being provided to effect such shifting.

With the arrangement described and with the gears positioned as shown in Fig. III, the drum 26 will obviously be driven in the same direction and at a higher rate of speed than the drum 27 by virtue of the difference in the ratios of the driving pinions 42, 43 and the gears 32, 35 with which they are in mesh. By shifting the pinions 42, 43 simultaneously to the dot-and-dash line position by means of the hand lever 44, a variation in the speed relation is effected without changing the rotative direction of the drums 26, 27. Obviously, suitable reversing means is associated with the source of power, hence, it is not deemed necessary to herein describe or illustrate the same as it forms no part of this invention. Furthermore, it is to be particularly noted that when one drum—e. g. 26—is clutched and pulling, the other drum —27— is turning in the same direction but slipping with respect to its drive gear.

Considering the use of the winding mechanism in connection with the material storage and handling plant of Figs. I and II, it will be apparent that the drag scraper 17 may be operated at a higher rate of speed during the idle or return travel than during the active or loaded travel, the operation being selectively controllable by means of the hand lever 44 in the manner previously ex-

plained. In the event of strain induced in the cable 18, differential action is permitted to take place between the drums 26, 27 under the flexibility afforded by the frictional cone couplings between said drums and the associated drive gears 32, 34 and 33, 35 fast on the drum shafts 28, 29, the apparatus being thus protected at all times against the possibility of injury.

Having thus described my invention, I claim:

1. In cable winding mechanism of the character described, winding drums for opposite ends of the cable freely mounted on separate shafts, friction couplings coupling the respective shafts and drums, high and low speed gears respectively associated with each of the shafts, and rigidly coupled high and low speed pinions adapted for simultaneous meshing respectively with the high speed gear of one drum shaft and the low speed gear of the other drum shaft, said pinions being shiftable with respect to said gears to enable change in the driving and speed relation of said drums.

2. In cable winding mechanism of the character described, winding drums for opposite ends of the cable freely mounted on separate shafts, high and low speed gears respectively associated with each of the shafts, integrally connected high and low speed pinions on an intermediate drive shaft adapted for simultaneous meshing respectively with the high speed gear of one drum shaft and the low speed gear of the other drum shaft, said pinions being shiftable with respect to said gears to enable change in the driving and speed relation of said drums, and friction coupling connections between the shafts and drums permitting differential action between said drums in the event of stress in the cable.

In testimony whereof, I have hereunto signed my name at Philadelphia, Pennsylvania, this 3rd day of May, 1926.

ROBERT H. BEAUMONT.
